UNITED STATES PATENT OFFICE.

JOHN OESTERLING, OF WHEELING, WEST VIRGINIA.

DESIGN FOR ORNAMENTATION OF GLASS-WARE.

Specification forming part of Design No. 5,318, dated October 17, 1871.

To all whom it may concern:

Be it known that I, JOHN OESTERLING, of Wheeling, in the county of Ohio and State of West Virginia, have invented a new and original Design for the Ornamentation of Pressed or Blown-Glass Vessels; and I hereby declare that the following is a full, clear, and exact description thereof, which will enable others skilled in the art to make and use the same, reference being had to the accompanying drawings forming part of this specification.

The nature of my design is fully represented

in the accompanying drawings, to which reference is made, the said design being a bunch of wheat hanging in a shield.

Having thus described my invention, I claim as new and desire to secure by Letters Patent—

The design for the ornamentation for various pressed or blown-glass vessels, as shown.

JOHN OESTERLING.
